MEANS FOR DELIVERING AND WINDING STRANDS, ETC

Filed Dec. 4, 1930

Inventor,

John E. Barbour,

By his Attorney

John Steward,

UNITED STATES PATENT OFFICE

JOHN E. BARBOUR, OF PATERSON, NEW JERSEY, ASSIGNOR TO NATIONAL NET & TWINE CO. INC., OF BOSTON, MASSACHUSETTS, A CORPORATION OF DELAWARE

MEANS FOR DELIVERING AND WINDING STRANDS, ETC.

Application filed December 4, 1930. Serial No. 499,875.

This invention relates to apparatus whereby flexible material, as a strand or strands, is withdrawn from a rotary supply thereof by winding the material on a suitable core which is revolved intermittently to effect the winding. For instance, in net-making machines the strands with which the shuttle strands are knotted and which are wound on revoluble supply spools become wound up, as component parts of the net formed, on a beam which is thus revolved. The intermittent action of this beam, especially if high speed is desired and the winding-up motions of the beam are consequently quick, produces by the draft on the strands overrunning of the spools forming the supply, which of course means an undesired slackening of the tension on the strands. The principal object of this invention is to construct apparatus of this character so that, regardless of the speed at which the apparatus is driven, this overrunning and the consequent slackening of the strands may be avoided.

The drawing shows the improved apparatus in side elevation.

Suitable supporting structure is afforded by the frame 1 and the creel 2.

Freely revoluble on the creel are the spools 3 forming the rotary supply of wound material *a*, which is here composed of strands individually wound on the spools and extending over a guide 2*a* thereon.

The mentioned core (here a beam) on which to wind the material is indicated at 4 as journaled in the frame 1.

On a part of the supporting structure, as the frame, is means movable forwardly and backwardly to alternately draw off the material from the supply 3 and release the same. This consists here of a lever 5 fulcrumed between its ends and having on one arm 5*a* a guide 6 for the material. This guide acts, crosswise of the material, to bend the same to effect the drawing-off action, and it may advantageously coact to this end with another guide or guides, as 6, which are here affixed to the frame. The terms "forwardly" and "backwardly" are here used to define the active (or drawing off) and return (or

release) movement of the means 5, respectively.

The core 4 is held against backward movement by a pawl 7. It is driven forwardly, to wind the material thereon, by a member 55 which is here rotative forwardly and backwardly concentrically therewith, as by being journaled on its trunnion 4*a*, and here comprising a clutch 8 having a spring-pressed pawl 9 cooperative with the ratchet teeth 4*b* 60 of the core. Any other reciprocating driver which is active when moving in one (here termed the forward) direction and inactive when moving in the other (here termed the backward) direction to rotate the core in 65 the direction for winding the material thereon will serve instead of the clutch and is within the scope of this invention.

Means, connecting the driver and the drawing-off means (here lever 5), synchronizes the forward and backward movements of the former with the backward and forward movements of the latter, thus: Moving with (here forming part of) the driver is a wheel 10 and connecting this wheel and the 75 arm 5*b* of the lever 5 is a flexible connection as a chain 11, such chain extending from the lever to the wheel and around the same, more or less, in the direction of its backward rotation and secured thereto. 80

Thus it will be seen that when the system comprising the driver 8, parts 10—11, and means 5 is moved back and forth each movement thereof in one direction results in a drawing-off of the material by means 5 85 while the core remains at standstill and each movement thereof in the other direction results in release of the material by the means 5 and winding up thereof on the core. Thus 90 the means 5, instead of the core, effects the drawing-off, and the core winds up what is thus drawn off by means 5. Since in the example the part 6 of the means 5 is a guide for the material moving transversely of the 95 same and thus tensioning it for its whole extent from the supply to the core and also moving back and forth in synchrony with the driver the core on performing each winding motion finds the material in a state of 100

tension and not slack, as is the case where the means 5 is absent.

Of course as the apparatus has been so far described there is a speed limit which can not be exceeded without the drawing-off action producing undesirable slack between the supply and means 5. Hence I provide means to drive the mentioned system so that its movement in the direction for drawing off the material from the supply shall be slower than its movement in the direction for effecting the winding movements of the core. In the example a cam 12 is continually rotated in one direction, say from some rotary element 13 of the machine, and its cam groove has engaged therewith a lever 14 which is connected with the driver 8 by a link 15. The cam groove has a portion 12a which suddenly approaches and a portion 12b which gradually recedes from the center of the cam, wherefore when portion 12a encounters the lever the latter suddenly rises to effect active movement of the driver, with corresponding sudden release movement of means 5, and when portion 12b encounters the lever the latter slowly falls, so that in the idle or backward motion of the driver the means 5 slowly acts to draw off the material from the supply. Any other means for moving the system comprising the driver, parts 10—11 and means 5 alternately fast and slow in the way indicated may of course be resorted to.

Having thus fully described my invention what I claim is:

1. In combination, supporting structure, a rotary supply of wound material therein, a rotary core in said structure on which to wind the material, means between the supply and core movable forwardly and backwardly to respectively draw the material from the supply and release the same, a forwardly and backwardly movable driver for the core active when moving forwardly and inactive when moving backwardly to rotate the core in the direction for winding the material thereon, and means, connecting the driver and first means, to synchronize the forward and backward movements of the former with the backward and forward movements of the latter, respectively.

2. In combination, supporting structure, a rotary supply of wound material therein, a rotary core on said structure on which to wind the material, means between the supply and core including a guide for the material and movable forwardly to bend the material and then back whereby to respectively draw the material from the supply and release the same, a forwardly and backwardly movable driver for the core active when moving forwardly and inactive when moving backwardly to rotate the core in the direction for winding the material thereon, and means, connecting the driver and first means, to synchronize

the forward and backward movements of the former with the back and forward movements of the latter, respectively.

3. In combination, supporting structure, a rotary supply of wound material therein, a rotary core in said structure on which to wind the material, means between the supply and core movable forwardly and backwardly to respectively draw the material from the supply and release the same, a forwardly and backwardly movable driver for the core active when moving forwardly and inactive when moving backwardly to rotate the core in the direction for winding the material thereon, means, connecting the driver and first means, to synchronize the forward and backward movements of the former with the backward and forward movements of the latter, respectively, and means to drive the system including the first means, driver and second means at a faster rate when the driver is moving forward than when it is moving backward.

4. In combination, supporting structure, a rotary supply of wound material therein, a rotary core in said structure on which to wind the material, means between the supply and core movable forwardly and backwardly to respectively draw the material from the supply and release the same, a forwardly and backwardly revolute driver for the core active when moving forwardly and inactive when moving backwardly to rotate the core in the direction for winding the material therein, and means to transmit a backward movement to the first means on each forward movement of the driver including a flexible connection attached to and extending around the periphery of the driver in the direction of its backward movement.

5. In combination, supporting structure, a rotary supply of wound material therein, a rotary core in said structure on which to wind the material, a lever engaged by the material and movable forwardly and backwardly to respectively draw the material from the supply and release the same, a forwardly and backwardly movable driver for the core active when moving forwardly and inactive when moving backwardly to rotate the core in the direction for winding the material thereon, and means, connecting the driver and lever, to synchronize the forward and backward movements of the former with the backward and forward movements of the latter, respectively.

In testimony whereof I affix my signature.
JOHN E. BARBOUR.
